Roman Lindyberg Inventor

UNITED STATES PATENT OFFICE.

ROMAN LINDYBERG, OF BROOKLYN, NEW YORK.

MEANS AND METHOD OF RECONDITIONING DAMAGED STEPS.

Application filed February 15, 1924. Serial No. 693,119.

To all whom it may concern:

Be it known that I, ROMAN LINDYBERG, a citizen of the United States, residing at Brooklyn, in the county of Kings and State 5 of New York, have invented new Means and Methods of Reconditioning Damaged Steps, of which the following is a specification.

This invention relates generally to the 10 reconditioning of broken and damaged steps on the stoops of buildings, or otherwise located, the invention being intended more particularly for application and use in connection with the reconditioning and repairing 15 of cement or concrete steps.

The invention has for a general object to provide a novel and improved means and method for reconditioning the damaged steps, repairing broken corners and edges 20 thereof, and resurfacing the tread of the step.

For further comprehension of the invention, and of the objects and advantages thereof, reference will be had to the following 25 description and accompanying drawing, and to the appended claims in which the various novel features of the invention are more particularly set forth.

Fig. 1 of the drawing is a perspective 30 view, with parts broken away, showing the application of the invention to the reconditioning of a cement step.

Fig. 2 is a transverse vertical sectional view of the step, this view being taken on 35 the line 2—2 of Fig. 1, the adjacent upper step being shown in end elevation.

According to my invention I provide a 40 frame member which is adapted to extend around the top edge of the broken or damaged step at the front and ends thereof. This frame member is preferably in the form of a channel iron, the size of the channel between the flanges being determined by the size of the projecting edging at the top 45 of the step, the width of the channel being somewhat greater than the depth of the edging, while the depth of the channel is preferably somewhat greater than the width or overhang of the said edging. This channel iron frame element comprises the main 50 central member 10 which, when in position, extends along the front of the step, and the end members 10' which are turned at right angles to the main member and extend along 55 the ends of the step. At the extremities of

these end members the channeled frame member is turned parallel to the main length thereof to form short extensions 10" which engage the rear side of the edging where the latter projects longitudinally beyond 60 the end wall of the vertical element or riser of the step.

Fixed at one end to the main length 10 of the channeled member are several hook-bolts 12, while the end members 10' each 65 have a like hook-bolt 12' fixed thereto. These bolts are of slightly less length than the width of the step, and project transversely with respect to the members to which they are attached into the space within 70 the frame. These bolts may be conveniently riveted at one end to the frame members and are formed at their other ends with the down-turned ends 14 which constitute the hooks thereof. These bolts are 75 preferably spaced above the lower flanges of the frame member a distance equal to the thickness of the edging so that when the frame is in position the bolts will extend across and rest upon the top face or tread 80 of the step to be repaired, while the bottom flanges of the frame member will engage closely under the projecting element constituted by the edging of the step.

In carrying out the reconditioning of the 85 step with my improved means and according to my invention a number of holes or sockets are formed in the tread 18 of the step in proper position to receive the hooked ends 14 of the various hook-bolts when the 90 frame is fitted on the edging 19 of the step. The frame is then sprung into place on the step and completely surrounds the edging thereof, the bolts 12, 12' extending over the tread of the step and having their hooked 95 ends 14 engaged in the sockets formed in the latter. The tread of the step is then faced with a filler or layer 20 of cement of a color to match that of the step, the thickness of this layer of cement being such as to bring 100 its top surface flush with the top edge of the metal frame. The cement thus fills the portion of the frame projecting beyond the step, extending downward in front of the edging of the step as indicated in Fig. 2 of 105 the drawing. After the cement has hardened the channel frame is painted a color to match the cement and the reconditioning of the step is complete. The step, when thus reconditioned is in all respects like a new 110

step, while, in addition, further breaking or damage at the edges or corners thereof is prevented by the protecting metal frame.

Having thus described my invention what I claim as new and desire to protect by Letters Patent of the United States is as follows:—

1. A device for use in reconditioning steps comprising a channeled frame member arranged to surround the edging of a step, and a number of hook-bolts fixed to said frame at one end and extending within the confines of the frame, said hook-bolts having their other ends turned downwardly.
2. A device for use in reconditioning steps comprising a channeled frame member arranged to surround the edging of a step, and a number of hook-bolts fixed to said frame at one end and extending within the confines of the frame, said hook-bolts having their other ends turned downwardly, said frame being of a depth between its flanges somewhat greater than the depth of the edging of the step to which said member is to be applied, said bolts being spaced above the lower flange of the frame member a distance equal to the depth of the edging of the step to which the frame is to be applied.
3. A device for use in reconditioning

steps comprising a channeled frame member arranged to surround the edging of a step, and a number of hook-bolts fixed to said frame at one end and extending within the confines of the frame, said hook-bolts having their other ends turned downwardly, said frame being of a depth between its flanges somewhat greater than the depth of the edging of the step to which said member is to be applied, said bolts being spaced above the lower flange of the frame member a distance equal to the depth of the edging of the step to which the frame is to be applied.

4. A reconditioned cement step having a channeled frame extending around the edging of the step with its bottom flange extending under and abutting against the bottom of the step edging, and its top flange extending over said edging and spaced above the tread of the step, a number of bolts fixed to said frame and extending across the tread of the step, said bolts having hooked ends engaging in sockets in said tread, and a cement facing on said tread flush as its top with the top edge of the said frame.

ROMAN LINDYBERG
